MINE CAR

Donald U. Rich, Teaneck, N. J., assignor to American Car and Foundry Company, New York, N. Y., a corporation of New Jersey

Application September 8, 1934, Serial No. 743,192

13 Claims. (Cl. 105—364)

This invention relates to improvements in mine and similar rail cars.

One object of this invention is to provide a mine car of maximum lading capacity.

5 Another object of this invention is to provide a mine car in which the floor or lading supporting bottom thereof is arranged in a horizontal plane below the centers of the car axles; the specific embodiment shown in this application 10 having the floor arranged in a horizontal plane entirely below the axles.

Mine cars are generally of either rotary dump, end dump or drop bottom construction. A mine car of the end dump type is disclosed in this application but obviously the car shown is adapted for rotary dumping within the spirit of the present invention.

Another object of this invention is the provision of a new and improved end construction 20 for the gate end of an end dump mine car.

Other objects and advantages of this invention will be apparent from the following description taken in conjunction with the accompanying drawings, in which:

25 Figure 1 is a side elevation of one end portion of the mine car of the present invention, the end construction thereof being shown in section;

Fig. 2 is a sectional view through an end portion of the mine car of the present invention, 30 the view being taken at the gate end of the car;

Fig. 3 is a top plan view of the portion of the car shown in Fig. 2;

Fig. 4 is an end view of the car of the present invention, the view being taken at the gate end 35 of the car;

Fig. 5 is a sectional view at the inside of the car looking toward the gate end thereof;

Fig. 6 is a sectional view on the line 6—6, Fig. 3, and

40 Fig. 7 is a fragmentary sectional view on the line 7—7, Fig. 3.

Referring now more particularly to the invention, the mine car shown therein comprises generally a body indicated at A and an underframe indicated generally at B, the underframe actually forming a part of the lading holding body A as will be more fully apparent hereinafter.

The car includes spaced side sills indicated at 2, said sills being substantially Z-shaped in section, and provided with upper and lower flanges 4 and 6 respectively. The lower flanges 6 of side sills 2 are inturned as shown more clearly in Figs. 4, 5 and 6 and serve to support a central lading bottom 8 formed of a metal plate or a series of 55 metal plates which extend between the side sills.

Secured to the upper flanges 4 of the side sills 2 and extending laterally outward therefrom are side floor portions 10 arranged substantially horizontal and hence parallel to the central floor portion 8, the side floor portion 10 being formed, in the instance shown, integral with the side walls 12 of the car body. For stiffening the side walls 12 the upper edge portions thereof are provided with beads 14.

The body A is stiffened also by the provision of 10 belts 16 which are secured as at 18 to the side walls 12 and side floor portions 10 and extend under the latter and also under the central floor portion 8 as clearly shown in Fig. 6.

Mine cars are sometimes provided with through 15 axles, that is, axles which extend through the side sills, stub axles, or drop axles. This is true of either mine cars in which the floor is above the axles or in which the floor is in a horizontal plane below the axle spindles. For purposes of 20 illustration only, the car of the present invention is of the through axle type, that is one in which the axles extend through the side sills. The axles are shown at 20 and are arranged in axle bearing elements 22 secured to the outer 25 surfaces of the webs of the side sills, these axles carrying wheels 24.

The side floor portions 10 are suitably apertured so that the wheels project therethrough, and said apertures are covered by wheel housings 26, the longitudinal walls 28 and 30 of which are inclined with respect to a vertical plane through the car; the outer longitudinal walls 30 diverging upwardly with respect to the side walls 12 as clearly shown in Fig. 6. The upper portions of the wheel housings 26 are also inclined upwardly toward the longitudinal center line of the car body.

One end of the car body is closed by a fixed end wall 32 connected to the end portions of the side 40 walls in any suitable manner as by rivets engaging the flanged portions of either the side or end walls or in any other suitable manner; it being conventional to connect the side and end walls of a mine car in fixed relation.

The opposite end portion of the car, termed the dumping end of the car, is provided with an end gate 34 hingedly connected by outside bail elements 36 to the car body as shown at the pivots 38, see Fig. 3.

The gate is suitably reinforced as is conventional in the art and is provided, substantially midway between its ends, with an aperture 40 through which a drawbar element 46 projects. The opposite end of the car is also provided with a drawbar 46. To stiffen the gate adjacent the 55

aperture 40 an angle 48 is secured to the gate by suitable fasteners 50. Both the gate and the fixed end wall may be and preferably are stiffened by vertically arranged reinforcing bars 52 5 as shown clearly in Figs. 1 and 2.

The central floor portion 8, in the instance shown, comprises a continuous metal plate, see Fig. 2. The axles 20 are arranged in a horizontal plane above the lower flanges 6 of the side 10 sills and preferably intermediate the upper and lower flanges of said sills and hence are entirely above the central floor portion 8, as clearly shown in Fig. 2. In the form of the invention 15 illustrated in the drawings in which the axles 20 extend through or penetrate the side sills, said axles are covered by axle housings indicated at 54, the end portions of which are flanged as at 56 and are welded to the side sills as shown at 20 58. The housings are secured to the floor 8 by fasteners 59. The axle housings each comprise a crown portion 62 which is curved on an arc and which is joined to upwardly curved side 25 walls 64, the arcs of which do not intersect. This is in contradistinction to an inverted U-shaped axle housing or one in which the side walls are gradually inclined upwardly toward either end of the car body. Gradually inclining the axle 30 housings upwardly results in a construction in which at least one side thereof is in a relatively straight line. This obviously reduces the lading 35 capacity of the car as, in an end dump mine car, the gradual upward incline of an axle housing is arranged at an angle with respect to the horizontal which corresponds to or is substantially the same as the angle of tilt of the car when 40 in end dumping position. By the provision of the axle housings shown herein in which no two points of the effective portions thereof are in the same horizontal plane, the discharge of lading 45 when the car is tilted endwise for dumping is facilitated without the corresponding loss of lading capacity and, still further, these housings 50 54 are substantially uniform in cross section and thus serve as braces between the side sills.

The mine car of the present invention also includes end structures now to be described. The end structures shown are substantially identical and each thereof comprises a unitary metal member in the form of an elongated Z-section 55 constituting a combined end sill and end deflector, said member being indicated generally at 66 and extending between the side sills 2 and having its rear edge portion substantially horizontal as shown at 68 and overlapped by an offset end 60 portion 70 of the central lading bottom 8. In the drawings the member 66 is shown as being a unitary pressing, though this is for illustrative purposes only and from the rear edge portion 68 the combined end sill and deflector member 66 slopes gradually upward in a straight line as shown at 72 to a point 74 adjacent the horizontal plane of the flanges 4 of the side sills from where the member 64 is projected horizontally outward as at 76 beyond the ends of the car 65 body to overlie a wood filler block or bumper cushioning member 78. The bumper block 78 is supported by the outwardly projected portion 80 of an end structure base plate 82 which is supported by and secured to the end belt 16 and extends rearwardly under the rear edge portion 68 70 of member 66 and is secured to said portion 68 and to the central floor portion 8 by suitable fasteners 86. The plate 82 is supported by the lower flanges 6 of the side sills and the forwardly projecting portion 80 thereof, in the instance shown, 75

is upwardly offset as clearly shown in Fig. 2, though this offset is not necessary as will be obvious.

Suitable fasteners such as the bolts 88 secure the wood block 78 in position between the projected end portion of the combined end sill and end deflector member 66 and the projected portion 80 of plate 82. The wood block 78 is provided with a vertical aperture 90 which is aligned with apertures in the projected portion 76 of member 66 and the offset end portion of plate 82 to receive a coupling pin 92 supported by the drawbar 46. A bumper plate 94 is provided having a vertically arranged bumping face as is conventional and upper and lower flanges 96 which project toward the lading body and respectively overlap and underlap the projected portion 76 of member 66 and the offset portion 80 of plate 82. The bumper plate is connected to block 78 in any suitable or desired manner. In some instances it may be desirable to provide a construction in which the upper flange 96 does not overlap the projected end portion of member 66 in order to avoid a positive connection of the bumper plate with the side sills through the medium of the member 66, in which event the projected portion of the member 66 may be cut out in a suitable manner so that the upper flange of the bumper plate may rest directly on the bumper block, the fasteners which secure the bumper plate to the bumper block passing only through the upper flange of the bumper plate and said bumper block without passing through the projected portion of member 66.

The drawbar 46 is secured within the lading body on the member 66 and projects through the aforementioned aperture 40 and is arranged in spaced relation above the bumper construction.

The plate 82 serves as a supporting element for a plurality of diaphragms adapted to stiffen and brace the end construction and to serve as members to take end thrust against the bumper. Adjacent the side sills 2 end diaphragms are indicated at 98 and have their webs 100 riveted as at 102 to the webs of the side sills, as clearly shown in Figs. 3 and 7. The diaphragms 98 have upper portions 104 which conform to the shape of the combined end sill and deflector member 66 and underlie the same and are fastened thereto as shown at 106. The end diaphragms 98 are provided with vertically arranged front faces 108 which serve as backing elements for the wood bumper block 78. Intermediate the end diaphragms 98 are a plurality of longitudinally arranged spaced diaphragms 110 secured to the base plate 82 and to the combined end sill and deflector member 66 and formed to provide front surfaces 112 against which the wood bumper block 78 bears, as clearly shown in Fig. 2. If deemed desirable the diaphragms which support the combined end sill and deflector member 66 may be transversely braced in any suitable manner.

From the description just above it will be apparent that the mine car of the present invention is adapted either for rotary or for end dumping and in the event of end dumping, the end construction includes and comprises a member which serves both as an end deflector to facilitate discharge of lading out of the car when the latter is tilted and also as an end traction structure or end sill. It will be obvious that the combined end sill and end deflector may be formed as a pressing or may be a casting. It is not absolutely essential that this member be wholly a unitary

member provided it functions as a combined end sill and end deflector element. The combined end sill and end deflector member is adapted to replace the usual end sill of the car as will be apparent. The end structure of the car body is suitably stiffened by means of the connecting elements between the side sills and end sills to thus prevent tendency of relative longitudinal movement of the side sills, and said end structure is further stiffened by a plurality of longitudinally arranged spaced reinforcing elements. Because of the connection of the combined end sill and end deflector with the side sills, tendency of relative sidewise movement or weaving of the underframe is eliminated. In the drawings the car is shown as having substantially identical end constructions though this is not altogether essential as in end dump cars the deflector function is only required at the dumping end of the car and it is not the intention to limit the present invention to a car in which the constructions at opposite ends of the car are identical.

While the drawings disclose a mine car having axles which penetrate the side sills it is not to be understood that the invention is limited to this particular type of car as obviously, within the spirit of the present invention, the car may be supported by stub axles and suitable axle bearings therefor such as are conventional in the art.

30 What is claimed is:

1. In an end dump mine car, side sills, a floor secured to the lower portions of the side sills, and means for connecting the end portions of the side sills, said connecting means replacing the usual end sill and comprising a unitary metal member between and connected to the sills and connected to the floor and formed to constitute a combined end sill and end deflector adapted to guide lading out of the car as the latter is tilted.

2. In an end dump mine car, side sills, a floor secured to the lower portions of the side sills, and means for connecting the end portions of the side sills, said connecting means replacing the usual end sill and comprising a unitary pressed metal member substantially of elongated Z-shape in section arranged between and connected to the side sills and also connected to the floor, said connecting means being so formed as to constitute a combined end sill and end deflector adapted to guide lading out of the car as the latter is tilted.

3. In an end dump mine car, side sills, a floor secured to the lower portions of the side sills, means connecting the end portions of the side sills, said connecting means replacing the usual end sill and comprising a unitary member connected to the floor and to the side sills and so formed as to constitute a combined end sill and end deflector adapted to guide lading out of the car as the latter is tilted, a bumper block underlying a part of said member, and bracing elements interposed between the bumper block and said member adapted to stiffen said member and formed to constitute end thrust means for said bumper block.

4. In an end dump mine car, side sills, a floor secured to the lower portions of the side sills, means connecting the end portions of the side sills, said connecting means replacing the usual end sill and comprising a unitary pressed metal member connected to said sills and to the floor and so formed as to constitute a combined end sill and end deflector for guiding lading out of the car as the latter is tilted, said member projecting beyond the ends of the side sills, a bumper

block underlying the projected portion of said member, a base plate secured to the floor and projecting beyond the ends of the side sills and underlying the bumper block to provide a support therefor, and bracing elements interposed between the bumper block and said member and connected to the latter and to said base plate and arranged in abutting relation with said bumper block.

5. In a mine car, the combination of side sills, axles in a plane above the lower portions of the side sills, a lading supporting floor in a plane below the axles, and a combined end deflector and end sill at one end portion of the car connected to the side sills and the floor and constituting the sole end sill member at that end of the car.

6. In a mine car, the combination of side sills, axles in a plane above the lower portions of the side sills, a lading supporting floor in a plane below the axles, a combined end deflector and end sill at one end portion of the car connected to the side sills and the floor constituting the sole end sill member at that end of the car, and housings covering the axles and secured to the floor.

7. In an end dump mine car, the combination of side sills, a floor supported by the lower portions of the side sills, axles having their spindles in a plane above the floor, and an end structure constituting the sole end sill member at that end of the car, said structure comprising a unitary element formed to provide a combined end sill and end deflector extending between the side sills and connected thereto and to the floor, said end structure being adapted to facilitate discharge of lading from the car when the latter is tilted.

8. In an end dump mine car, side sills, a floor supported by the lower portions of the side sills, a gate at one end of the car and an end construction comprising an end sill member of elongated Z-shape in section having its lower flange connected to the floor and its upper flange projecting beyond the gate and its web inclined upwardly toward the gate whereby to constitute deflecting means for guiding lading out of the car as the latter is tilted for end dumping, said end construction constituting the sole end sill at that end of the car.

9. In a mine car, side sills, a floor supported by the lower portions of the side sills, a gate at one end of the car, an end construction replacing the usual end sill of the car and comprising a unitary member extending between and connected to the side sills and so formed as to constitute a combined end sill and lading deflector, longitudinally arranged braces underlying and connected to said member, a base plate secured to said member and supporting said braces, said plate and member projecting in spaced relation beyond the gate, and a cushioning element interposed between said plate and member and bearing against said braces.

10. In a mine car, side sills, a floor secured to the lower portions of the side sills and having a portion thereof at one end of the car sloping upwardly and projecting beyond the side sills whereby to provide a combined end sill and deflector means for guiding lading out of the car as the latter is tilted for end dumping, said upwardly sloping and projecting portion replacing the usual end sill of the car, a bumper supporting plate secured to the floor, a bumper block supported by said plate, and end thrust members underlying and secured to the combined end sill.

and deflector means and supported by the bumper supporting plate and with which the bumper block abuts.

11. In an end dump mine car, side sills, a lading supporting floor secured to the side sills, and having at least one end portion thereof formed to provide a transverse end structure extending between the side sills at their end portions and constituting a combined end deflector and end sill, said portion being the sole end sill for the corresponding end of the car and being adapted to guide lading out of the car when the car is tilted for end dumping.

12. In an end dump mine car, side sills, and a

floor secured to and connecting the side sills and having a portion thereof at the dumping end of the car upwardly inclined to provide a lading deflecting element, said upwardly inclined floor portion replacing the usual end sill of a car.

13. In an end dump mine car, side sills, a floor secured to and connecting the side sills and having a portion thereof at the dumping end of the car upwardly inclined to provide a lading deflecting element, said upwardly inclined portion constituting the sole end sill element at that end of the car, and bracing means for said deflecting element underlying and secured thereto.

DONALD U. RICH.
